CLAIM

The ornamental design for a hanger for small articles, as shown and described.

DESCRIPTION

FIG. 1 is a perspective view of a hanger for small articles according to the invention;

FIG. 2 is a front elevation view of the hanger for small articles of FIG. 1;

FIG. 3 is a rear elevation view of the hanger for small articles of FIG. 1;

FIG. 4 is a right side elevation view of the hanger for small articles of FIG. 1, with the left side elevation view being symmetrical;

FIG. 5 is a top plan view of the hanger for small articles of FIG. 1;

FIG. 6 is a bottom plan view of the hanger for small articles of FIG. 1;

FIG. 7 is a cross-sectional view of the hanger for small articles through line 7-7 shown in FIG. 2;

FIG. 8 is a cross-sectional view of the hanger for small articles through line 8-8 shown in FIG. 2;

FIG. 9 is a partially enlarged view of the hanger for small articles through portion 9-9 shown in FIG. 8;

FIG. 10 is a perspective view of the hanger for small articles of FIG. 1 for the state where the hook is rotated by 90 degrees with respect to the base;

FIG. 11 is a top plan view of the hanger for small articles of FIG. 1 for the state where the hook is rotated by 90 degrees with respect to the base; and,

FIG. 12 is a front elevation view of the hanger for small articles of FIG. 1 for the state where the hook is rotated by 90 degrees with respect to the base.

The broken line showing of the hanger for small articles depicts environment and forms no part of the claimed design.
